UNITED STATES PATENT OFFICE.

SIDNEY O. BIGNEY, OF ATTLEBORO, MASSACHUSETTS, ASSIGNOR TO BRISTOL MANUFACTURING COMPANY, A CORPORATION OF RHODE ISLAND.

DESIGN FOR A BACK FOR BRUSHES OR SIMILAR ARTICLES.

SPECIFICATION forming part of Design No. 36,245, dated March 17, 1903.

Application filed February 7, 1903. Serial No. 142,418. Term of patent 3½ years.

To all whom it may concern:

Be it known that I, SIDNEY O. BIGNEY, a citizen of the United States, residing at Attleboro, in the county of Bristol and State of Massachusetts, have invented a certain new, original, and ornamental Design for the Back of a Brush or Similar Article, of which the following is a specification.

The drawing is a plan view of a brush or mirror back embodying my new design, wherein A represents the body portion, C the handle, and B an intermediate swelled portion.

The leading or material feature of my design is as follows: The body ornamentation comprises an irregular marginal beading *a*, whose inner margin is broken at the top by downwardly - directed oppositely - disposed scrolls *b*, which form the crest ornamentation.

Upon the escutcheon is the representation of a landscape, including the representation of

horses with riders mounted thereon accompanied by dogs. Extending axially along the face of the handle is an unornamented strip *c*, flanked by a deep-curved beading *d* on either side. The handle terminates with ²⁵ circular ornament *e*.

It is obvious that my new design is applicable to mirror-backs and similar articles.

Having described my invention, what I claim as new, and desire to secure by Letters ³⁰ Patent, is—

The ornamental design for the back of a brush, or similar article.

In testimony whereof I have affixed my signature in presence of two witnesses.

SIDNEY O. BIGNEY.
